(57) **CLAIM**

The ornamental design for a headlamp for an automobile, as shown and described.

DESCRIPTION

FIG. 1 is an outside elevational view of a headlamp for an automobile in accordance with a first embodiment of our new design;

FIG. 2 is an inside elevational view of the headlamp for an automobile in accordance with the first embodiment of our new design of FIG. 1;

FIG. 3 is a top plan view of the headlamp for an automobile in accordance with the first embodiment of our new design of FIGS. 1 and 2;

FIG. 4 is a bottom plan view of the headlamp for an automobile in accordance with the first embodiment of our new design of FIGS. 1 to 3;

FIG. 5 is a front side elevational view of the headlamp for an automobile in accordance with the first embodiment of our new design of FIGS. 1 to 4;

FIG. 6 is a rear side elevational view of the headlamp for an automobile in accordance with the first embodiment of our new design of FIGS. 1 to 5; and,

FIG. 7 is a front side perspective view of the headlamp for an automobile in accordance with the first embodiment of our new design of FIGS. 1 to 6.

A second embodiment of our new design is identical to the first embodiment except that the inside elevational view of FIG. 2 and the rear side elevational view of FIG. 6 form no part of the claimed design. In addition, in the second embodiment, the appearance of the rear side structures and inside side structures of the headlamp for an automobile as seen in FIGS. 1, 3, 4, 5 and 7 is for purpose of illustrating the boundaries of the exterior surface of the outside of the headlamp for an automobile, and forms no part of the claimed design. Our new design includes the mirror image of the headlamp for an automobile shown in FIGS. 1 to 7.
